COOLING SYSTEM FOR LIQUID COOLED INTERNAL-COMBUSTION ENGINES

Leonard P. Traxel, Chicago, Ill.

Application July 14, 1948, Serial No. 38,621

4 Claims. (Cl. 123—41.1)

1

This invention relates to improvements in cooling systems for liquid cooled internal combustion engines and refers particularly to a device employable with the usual internal combustion engine radiator for diverting heated fluid from a hotter portion of the radiator to a position in front of the radiator and employing the heat radiated and/or conducted therefrom to heat a colder portion of the radiator under certain conditions of operation of the engine.

The function and operation of the usual radiator of a liquid cooled internal combustion engine is well known as is also the usual circulating system for the liquid coolant in the conventional internal combustion engine. In general, the radiator comprises essentially a heat exchanger wherein heated coolant from the engine jacket is passed to the top of the radiator and passes downwardly through the radiator wherein the liquid is cooled by the passage of air through the honeycomb tubes of the radiator, the air being inducted through the honeycomb cells by a mechanically operated fan. The cooled liquid is then drawn from the bottom of the radiator and passed, usually by a pump, to the jacket of the engine to maintain the engine at a desired operating temperature.

In cold weather, if water is used as the coolant there is a likelihood of the water freezing in the cooling system if the ambient temperature is below freezing. When the cooling system is frozen, the frozen liquid in the water jacket of the engine is quickly thawed by operation of the engine. However, the radiator, being remote from the high temperatures of the engine remains frozen and, hence, circulation of the water is prevented. In a short period of engine operation under these conditions the water in the engine jacket boils and the hot vapors escape through the usual overflow pipe provided at the top of the radiator. After a short period of operation the jacket water all boils off and the temperature of the engine soars to dangerous heights, eventually destroying the engine if the operation is continued. Paradoxically, all through this operation the remaining portion of the cooling system, the radiator, remains frozen preventing circulation of the water.

In some instances, even during normal operation of the engine, when a sudden drop in atmospheric temperature occurs, the water in the radiator may freeze while the engine is operating leading to a condition similar to that hereinbefore described.

As a feature of my invention I provide means

2

for utilizing the high temperature vapors or steam generated in the engine jacket, by conduction, convection and/or radiation, to impart sufficient heat to the colder portions of the cooling system to prevent the water therein from freezing and, hence, proper circulation of the coolant through the entire system is maintained.

Broadly, my invention contemplates connecting a secondary heat exchange device to the top of the usual radiator, using this device as the radiator overflow and, in addition, positioning the device in a relationship with the colder portions of the radiator such as to transfer the heat from the vapors passing through said overflow to the water in the colder portions of the radiator.

The objects and advantages of my invention will be more apparent from the accompanying drawing and following detailed description.

In the drawing, Fig. 1 is a front elevational view of a conventional radiator, parts of the overflow heat exchanger being shown in section.

Fig. 2 is a side elevational view of the radiator, a fragmentary portion of the internal combustion engine being shown.

Referring in detail to the drawing, 1 indicates a fragmentary portion of an internal combustion engine of the liquid-cooled type. A radiator 2 is employed with the engine 1 and is illustrated as the type having the usual honeycomb cells or tubes 3. A cooling water outlet 4 connects into the upper portion of the jacket of the engine, said outlet being connected to a nipple 5 at the upper portion of the radiator 2 by a flexible conduit 6.

A discharge nipple 7 connects into the lower portion of the radiator 2, said nipple being connected by flexible conduit 8 to a water pump (not shown) of the conventional type. As is well known, the discharge side of the water pump connects into the lower portion of the engine jacket and, hence, a circuit for the passage of liquid to and from the engine to the radiator is formed.

A fan 9, driven by belt 10 is mounted upon the engine block between the engine and the honeycombed portion of the radiator. said fan, when driven, acting to draw air through the radiator to cool the liquid circulated therethrough.

In the usual radiator construction an overflow pipe open to the atmosphere is connected into the upper portion of the radiator so as to prevent the establishment of superatmospheric pressure in the radiator and cooling system generally when excessive vaporization of the liquid coolant may occur. For convenience, such pipes were disposed

55 behind the radiator, that is, on the engine side

of the radiator and discharged beneath the radiator. Such pipes also provided an overflow for excess liquid which may have been introduced into the system, especially when the liquid was introduced when the engine was cold.

In the present invention, I contemplate an overflow pipe 11 which may be connected into the upper portion of the radiator 2. For convenience, the pipe 11 is shown as being connected to the filling nipple 12, but it is to be understood that said pipe may be connected to any part of the top of the radiator, preferably, of course, above or at the normal liquid level in the radiator.

The pipe 11 is connected to a header 13 to which one or more heat-transferring discharge pipes 14 are connected, said pipes being open to the atmosphere at their opposite ends which are disposed adjacent the bottom of the radiator. Suitable bracket means 15 may be employed to support the pipes 14.

As a feature of my invention the pipes 14 are disposed in heat conductive relationship to the front portion of the radiator whereby the air induced by the fan 9 passes over said pipes before passing through the cell-portion 3 of the radiator. In this manner heat which may be given off by the pipes 14 may be transferred to the liquid in the radiator.

The pipes 14 may be mounted in spaced relationship to the front of the radiator in which case heat will be derived therefrom and passed to the radiator by convection, that is, the heating of the air passing the tubes and the subsequent transfer of such heat to the cells of the radiator, and by radiation from the pipes 14. Of course, extended surfaces, or fins, (not shown), may be carried by the pipes 14 in which case the heat transfer will be more efficient.

Inasmuch as the fundamental concept of my invention contemplates passage of heat from the pipes 14 to the liquid in the radiator, said pipes may be in heat conductive contact with the radiator cells wherein the transfer will be accomplished by conduction as well as convection and radiation.

The arrangement illustrated and described hereinbefore is adaptable to existing installations with only a minimum of changes being made in the existing structures. As a specialized item of equipment the radiator may be constructed with the pipes or equivalent heat-transferring passages built into the radiator, the latter constituting a separate circuit for fluid from the cooling system circuit proper.

In operation, when temperatures are encountered which will tend to freeze the cooling liquid of the engine, the liquid in the radiator normally freezes first and is last to thaw. The result of the liquid freezing in the radiator is to interrupt the circulation of the cooling liquid. Hence, the coolant in the engine quickly raises in temperature and is converted into steam which passes upwardly through conduit 6 to the top of the radiator. Heretofore the steam thus entering the radiator merely passed out through the overflow, the overflow by virtue of its position along the inside of the radiator accomplishing no function other than to relieve the system of the steam pressure.

In my invention, the hot steam heats the pipes 14 which, being disposed in front of the radiator, permit the heat therefrom to be transferred by the fan 9 to the frozen radiator. In this manner automobiles, for instance, with frozen radiators can be operated for an indefinite period of time

without causing serious overheating, merely by replenishing the liquid lost in steam. In addition, there will be no tendency for the radiator to freeze while the engine is in operation since such a tendency would be accompanied by interruption of circulation of the coolant and hence steam would soon thaw the freezing radiator and permit circulation to be resumed.

In view of the fact that water can be used as the coolant even below freezing temperatures without causing serious overheating, as long as the engine is running and the water lost in steam is replenished, for excessively low temperatures a lesser amount of anti-freezing material may be used so long as the engine when not in operation is in an atmosphere of not too low a temperature.

I claim as my invention:

1. In a cooling system for a liquid cooled internal combustion engine having a radiator for liquid coolant, a fan positioned behind said radiator to induce air through said radiator, a conduit connecting the upper portion of the engine and the upper portion of the radiator, and a conduit connecting the lower portion of the engine and the lower portion of the radiator, an overflow pipe connected into the upper portion of the radiator, a plurality of imperforate heat-radiating pipes connected to said overflow pipe, said heat-radiating pipes being positioned in front of said radiator and in heat conductive relationship with said radiator adjacent the front portion thereof, said heat-radiating pipes being open to the atmosphere at their ends.

2. In a cooling system for a liquid cooled internal combustion engine having a radiator for liquid coolant, a fan positioned behind said radiator to induce air through said radiator, a conduit connecting the upper portion of the engine and the upper portion of the radiator, and a conduit connecting the lower portion of the engine and the lower portion of the radiator, an overflow pipe connected into the upper portion of the radiator, a header connected to said overflow pipe, a plurality of conduits connected to said header, said last mentioned conduits being in heat conductive relationship with the front portion of the radiator and being open to the atmosphere at their ends.

3. In a cooling system for a liquid cooled internal combustion engine having a radiator for liquid coolant, a fan positioned behind said radiator to induce air through said radiator, a conduit connecting the upper portion of the engine and the upper portion of the radiator, and a conduit connecting the lower portion of the engine and the lower portion of the radiator, an overflow pipe connected into the upper portion of the radiator, a header connected to said overflow pipe, a plurality of conduits connected to said header, said last mentioned conduits being in heat conductive relationship with the front portion of the radiator and in the path of the air drawn through the radiator by the fan, said conduits being open to the atmosphere at their ends.

4. In a cooling system for a liquid cooled internal combustion engine having a radiator for liquid coolant, a fan positioned behind said radiator to induce air through said radiator, a conduit connecting the upper portion of the engine and the upper portion of the radiator, and a conduit connecting the lower portion of the engine and the lower portion of the radiator, an overflow pipe connected into the upper por-

tion of the radiator, a plurality of conduits positioned in front of said radiator in the path of the air drawn through the radiator by the fan, means connecting said pipe to said last mentioned conduits, said latter being open to the atmosphere at their ends.
